METALWORKING

Richard M. Schumacher, Chicago, Ill.

Application August 28, 1948, Serial No. 46,669

2 Claims. (Cl. 80—40)

1

My invention relates to metal working and includes among its objects and advantages a simplified procedure for producing narrow strips of sheet metal from wide strips, with the edges of the narrow strips rounded.

In the accompanying drawings:

Figure 1 is a partially diagrammatic plan view of equipment according to the invention;

Figure 2 is a side elevation of the same, partly in section;

Figure 3 is a detail view as in section on line 3—3 of Figure 1;

Figure 4 is a detail section on line 4—4 of Figure 1; and

Figure 5 is a detail of a modified lower supporting means.

In the embodiment of the invention selected for illustration, the equipment includes a conventional support 10 for the take-off roll 12 from which the parent strip 14 is unwound. Ordinarily, the roll 12 can be permitted to unwind without restraint, but if the reach between the roll and the table 16 happens to tend to kink, a slight drag may be applied to the roll, as by extending the shaft 18 through an additional bearing 20 and applying a conventional friction brake indicated at 22.

On the table 16 the parent strip is carried under conventional slitting means indicated as a shaft 24 and a series of cutters 26, which subdivide the strip into a plurality of much narrower scion strips, which may be of the same or different widths. I have indicated in the drawing six strips all of the same width. After passing the cutter, the six scion strips will lie in the same plane with their edges substantially in contact, but the cut edges will be rough and burred, and it is necessary to round these edges to render the product fit for further use.

After passing the cutter, the scion strips pass between the pair of rolls 30 and leave the table 16 to pass through edge-finishing means, indicated as mounted on a separate table 32. To finish the strips, it is necessary to pass each strip between a pair of grooved rolls, the grooves of which have rounded bottoms adapted to round and smooth the edges of the strip; but with the strips all in the same plane, the edges to be rounded are inaccessible. Identifying the individual strips for convenience by the reference characters 34, 36, 38, 40, 42 and 44, I guide the strips 34 and 40 across the table 32 at one predetermined level. The strips 36 and 42 are guided at a higher level to leave sufficient clearance for edging rolls to operate on the strips 34 and 40.

2

The strips 38 and 44 are guided at a still higher level and leave sufficient clearance for edging rolls to operate on the strips 36 and 42. In the embodiment illustrated, this brings the strip 38 high enough above the strip 40 so that there is room below it for the roll 46 operating on the adjacent edge of the strip 36, and room below that for another roll 48 operating on the adjacent edge of the strip 40.

10 As clearly indicated in Figure 3, this brings the rolls 46 and 48 more or less superposed when viewed in elevation longitudinally, but by setting the rolls for the strips 36 and 42 longitudinally offset from those for the strips 34 and 40, by a distance at least equal to the diameter of one roll, it is possible to have the necessary clearances for the supporting means for all the rolls, and clear passageways for all the strips. For instance, the rolls for the strips 34 and 40 are each mounted on individual blocks 50 (see Figure 4), each slideable transversely in guides 52, forming part of the table 32, and locked in adjusted position, as by set screws 54. The rolls for the strips 38 and 44 are all supported from 20 the transverse shaft 56, by means of brackets 58, having hubs 60 slideable on the shaft. The rolls for the edges of strips 36 and 42 adjacent the lower strips 34 and 40 are supported from above by identical brackets 58 slideable on the transverse shaft 62. The edges of the strips 36 and 25 42 adjacent the higher strips 38 and 44 are engaged by rolls on supports 64 identical with the supports 50, except that they project upwardly to the proper level.

30 Beyond the table 32 the strips are guided back into a common plane, by means of an idler roller 66, the ends of which are vertically slideable in slots 68 in the end standards 70. Beyond the roller 66 the reassembled finished scion strips are 35 wound up into a unitary package 72, which constitutes six juxtaposed rolls, each roll constituting the entirety of one scion strip.

I prefer to apply most of the power for drawing the material through the equipment, at the 40 receiving roll 72, as indicated by the sprocket 74 on the end of the shaft 76. In operating such a unit, an overload slip clutch in the shaft 76 at 45 78 is a convenient and useful precaution. Normally it is best to supply enough driving power to the cutters 26, as by means of the sprocket 80, to fully carry the cutting load. In handling a wide variety of thicknesses and qualities of metal, it will be obvious that sometimes greater smoothness and uniformity of 50 movement can be secured by delivering power to

the rolls 30 also, by means of the sprocket 82 and the relatively light slip clutch 84. To secure correct dimensions for all the finished strips, I follow the usual practice of trimming each edge of the parent strip and winding the trimmings up on the waste roller, indicated at 86, Figure 2.

Others may readily adapt the invention for use under various conditions of service, by employing one or more of the novel features disclosed, or equivalents thereof. For instance, where the strips are very narrow, it may be necessary to have four or five strips arranged in echelon in each cascade, as distinguished from two cascades of only three strips each. And under most conditions of installation, the slight angularity of the strips 33 and 44 where they enter the edging rolls will not be enough to interfere with the edging. But in the specific construction shown, all the sets of rollers supported from the shaft 56 can be adjusted by rotation around the shaft 56 to align the grooves exactly with the incoming strip. And to make a similar adjustment available for the strips 36 and 42, it is only necessary to replace a set of guides 52 with a transverse shaft 88, so that all the edging rolls, whether supported from above or below, can be similarly tilted into perfect alignment with the incoming strip.

As at present advised with respect to the apparent scope of my invention, I desire to claim the following subject matter:

1. Equipment for forming smooth-edged scion strips from a plurality of rough-edged longitudinally moving scion strips coming toward the equipment juxtaposed and in a common plane, comprising, in combination: a pair of edging rolls for each scion strip; said rolls being positioned to receive and deform the edges of the strips, while guiding the strips in longitudinal movement; said pairs of rolls being offset both vertically and horizontally with respect to each other in a plurality of echeloned closely overlapping cascades; the cascades being offset horizontally but aligned vertically with corresponding pairs of rolls of each cascade in the same horizontal plane, a top frame support means above and a bottom frame support means below the cascades, roll supports extending down from the top frame support means for supporting each roll of the top pairs of rolls of said cascades, roll supports

extending up from the bottom frame support means for supporting each roll of the bottom pairs of rolls of said cascades, roll supports extending down from the top frame support means for supporting one roll of each pair of intermediate rolls of said cascades and roll supports extending up from said bottom frame support means for supporting the other rolls of said intermediate pairs.

2. Equipment for forming smooth-edged scion strips from a plurality of rough-edged longitudinally moving scion strips coming toward the equipment juxtaposed and in a common plane, comprising, in combination: a pair of edging rolls for each scion strip; said rolls being positioned to receive and deform the edges of the strips, while guiding the strips in longitudinal movement; said pairs of rolls being offset both vertically and horizontally with respect to each other in a plurality of echeloned closely overlapping cascades; the cascades being offset horizontally but aligned vertically with corresponding pairs of rolls of each cascade in the same horizontal plane, a top frame support means above and a bottom frame support means below the cascades, roll supports extending down from the top frame support means for supporting each roll of the top pairs of rolls of said cascades except the outermost roll of the first pair, roll supports extending up from the bottom frame support means for supporting each roll of the bottom pairs of rolls of said cascades except for the outermost roll of the last pair, roll supports extending down from the top frame support means for supporting one roll of each pair of intermediate rolls of said cascades and roll supports extending up from said bottom frame support means for supporting the other rolls of said intermediate pairs, said outermost rolls being supported on either of said roll supports.

RICHARD M. SCHUMACHER.
